ORNAMENT AND ATTACHMENT THEREFOR

Filed May 31, 1930

UNITED STATES PATENT OFFICE

PAUL E. FENTON, OF THOMASTON, CONNECTICUT, ASSIGNOR TO SCOVILL MANUFACTURING COMPANY, OF WATERBURY, CONNECTICUT, A CORPORATION OF CONNECTICUT

ORNAMENT AND ATTACHMENT THEREFOR

Application filed May 31, 1930. Serial No. 458,854.

This invention relates to an ornament for use primarily upon various articles of apparel, such, for example, as arctics, shoes, pocket-books or purses, hand-bags and also upon other articles which employ snap and other separable fasteners, particularly when such fasteners occupy conspicuous positions upon the articles.

In articles of apparel and the like provided with separable fasteners, it is at present customary to make the portions of such fasteners, which are conspicuously located, of the same colors as the articles, or of such colors as will artistically harmonize or contrast with the colors of the articles.

It has been found that the artistic and attractive effect of this coloring may be materially enhanced and set off by the addition of a bright or contrastingly colored ornament, such as a polished, plated, coated or otherwise treated member of metal or other suitable material and of any desired ornamental configuration and surface ornamentation, preferably interposed between the colored fastener part and the portion of the article upon which the fastener part is arranged.

The object of the invention is to provide an ornament of the kind referred to, which will be of neat, attractive and artistic appearance, simple in construction, easy to manufacture, and capable of production in large quantities at low manufacturing cost, and which, moreover, may be applied or attached to an article simultaneously with and by an element of a separable or other fastener.

The invention comprises an ornament in the form of a flat or depressed plate of any desired configuration and ornamental finish; this plate being so formed as to be readily attached to an article, preferably by means of a member of a separable fastener or button, and a portion of such element being exposed upon the outer surface of the ornament and preferably colored the same as or in contrast with the color of the article, as will be hereinafter more fully explained and finally claimed.

In the accompanying drawings illustrat-

ing the invention, in the several figures of which like parts are similarly designated, Figure 1 is a side elevation of an arctic or "zipper", the closure strap of which is provided with the ornament of this invention. Fig. 2 is a perspective view illustrating the application of the ornament of the invention to a hand-bag, purse or pocket-book. Fig. 3 is an enlarged plan view of an ornament plate embodying the features of the invention, and Fig. 4 is a half section and side view thereof. Fig. 5 is a plan view of the ornament attached to an article by means of an element of a separable fastener, and Fig. 6 is a sectional side view thereof. Fig. 7 is a sectional side view of a suitable stud member for cooperation with the socket member of the separable fastener of Fig. 6. Figs. 8 and 9 are a plan view and a sectional side view, respectively, of a modified form of the ornament plate of the invention.

In its preferred form, as shown in Figs. 1 to 6 inclusive, the ornament of the invention includes a plate 1, preferably of metal, polished, plated, coated or otherwise treated to enhance its attractiveness and ornamental character, and of any desired ornamental and artistic configuration, and it may also be etched, engraved, embossed or otherwise ornamented upon its exposed surface. This plate is recessed or depressed, as indicated at 2, and is provided with an appropriately located aperture 3, for a purpose later explained.

The ornament may be applied or affixed to an article by any desired attaching means, but, in the embodiment of the invention illustrated, it is preferably attached by, and forms a combination with, an element or part of a separable or snap fastener. As shown in Figs. 5, 6 and 7, this element is the resilient socket member of a snap fastener of substantially the type disclosed in my co-pending application Serial No. 436,210, filed March 15, 1930. This fastener element comprises a finish cap or shell 4 forming a head which may be coated or otherwise treated to give it a distinctive color, and it may also be given other surface ornamentation if desired. The flange 5 of this shell or cap is

closed in around the off standing lip 6 of the resilient socket piece 7 which is formed for snap action over the head 8 of a complementary rigid stud.

- 5 The depression or recess 2 of the ornament plate 1 is of a size and depth to receive the head formed by the shell or cap 4 of the fastener element to such an extent that the projecting portion thereof will provide a neat and attractive button or dome-like projection relatively to the exposed surface of the plate 1 and when these two parts are thus arranged the socket piece 7 will project through the aperture 3 of the plate 1.
- 10 15 The ornament, which preferably includes the ornament plate 1 and the outwardly visible portion of the head formed by the cap or shell 4, is attached to an article, such as the strap 9 of an arctic 10 (Figs. 1, 5 and 6) by providing an opening 11 in the article and passing the socket piece 7 through such opening and then setting the parts upon the article by clinching the barrel 12 of an eyelet between the flange 5 of the shell 4 and the offstanding lip 6 of the socket piece 7, as indicated at 13. The plate 1 is thus interposed between the article and the shell 4 of the fastener and is rigidly attached to the article in adjusted position, and the depressed portion 2 causes it to stand off or away from the article, thus not only enhancing its attractiveness but making it easy to grasp when it is located in a position which makes this desirable.
- 20 25 30 35 40 45 50 55 60 65 70 75 80 85 90 95 100 105 110 115 120 125 130
- As shown in Fig. 5, the article is of a blue color, and the shell or cap 4 presents a head which is also blue to match the article. In contrast with the blue color of these parts the ornament plate 1 may be nickel-plated or otherwise made of a contrasting brightness or color. The combination and coloring of the parts in this manner provides a striking and attractive ornamentation.

As hereinbefore indicated, the shell or cap 4 may be colored to produce a head in contrast with the color of the article, or it may be polished or plated. Similarly, the plate 1 may be colored, the main object being the provision of an ornamental and attractive contrast or blend or combination of colors; or the article and the ornament, including the parts 1 and 4 may be of the same color. If desired, the depression or recess 2 may be omitted and the ornament plate made flat, as shown at 1' in Figs. 8 and 9, and will be provided with an aperture 3'. In such case the plate will lie flat against the article and the ornamental cap or shell of the attaching element will stand away from the plate.

No matter which form of ornament plate is used, it will be apparent that the object of the invention will be served. Either type of ornament plate is easily and cheaply manufactured, and either type can be readily

applied and attached to an article by a member of a separable fastener or other device which, at the same time, forms a part of the ornament.

Moreover, no special machinery is necessary for applying the ornament plate to an article. It may be applied by the fastener setting machine simultaneously with the setting or attaching of the fastener part upon the article.

Various changes and modifications, in addition to those specifically referred to, are considered to be within the spirit of the invention and the scope of the following claims.

What I claim is:—

1. An ornament for articles of apparel and the like, comprising an ornament plate, and means for attaching said plate to an article, said attaching means comprising a separable fastener element having a finish cap, said plate interposed between said article and said cap, and said cap forming an ornamental part of the ornament.
2. An ornament for articles of apparel and the like, comprising an ornament plate and attaching means therefor, said attaching means comprising a separable fastener element having a head, said plate being interposed between said article and said head and permanently attached by said attaching means, and said head overlying a portion of said plate and forming an ornamental part of the ornament.
3. An ornament for colored articles of apparel and the like, comprising an ornament plate and attaching means therefor, said attaching means comprising a separable fastener element having a head, said plate being interposed between said article and said head and permanently attached by said attaching means, and said head overlying a portion of said plate and being colored in harmony with the color of the article and forming an ornamental part of the ornament.
4. An ornament, comprising an ornamental plate of appropriate design and having a depression to receive a medium for fastening the plate to an article, such fastening medium comprising a separable fastener element provided with a head overlying said plate and having a color surface to harmonize with the color of the article.

In testimony whereof I have hereunto set my hand this 29th day of May, A. D. 1930.

PAUL E. FENTON.
